UNITED STATES PATENT OFFICE.

JULIUS F. ADAMS, OF PITTSBURGH, PENNSYLVANIA.

DESIGN FOR A FIREPLACE-GRATE.

55,228.

Specification for Design.

Patented May 25, 1920.

Application filed September 27, 1919. Serial No. 326,994. Term of patent 7 years.

To all whom it may concern:

Be it known that I, JULIUS F. ADAMS, a citizen of the United States, residing at Pittsburgh, in the county of Allegheny and State of Pennsylvania, (post-office address 103 Park avenue, in the said city,) have invented a new, original, and ornamental Design for a Fireplace-Grate, of which the following is a specification, reference being had to the accompanying drawing, forming part thereof.

The figure is a front view of a fireplace grate, showing my new design.

I claim:

The ornamental design for a fireplace grate, as shown.

JULIUS F. ADAMS.
